UNITED STATES PATENT OFFICE.

JOHN ASHTON DOBLE, OF WALTHAM, MASSACHUSETTS.

VAPOORIZING APPARATUS FOR HYDROCARBON FUELS.

1,151,090.

Specification of Letters Patent. Patented Aug. 24, 1915.

Application filed February 4, 1914. Serial No. 816,587.

To all whom it may concern:

Be it known that I, JOHN ASHTON DOBLE, a citizen of the United States, and resident of Waltham, county of Middlesex, and State 5 of Massachusetts, have invented certain new and useful Improvements in Vaporizing Apparatus for Hydrocarbon Fuels, of which the following is a specification.

This invention relates to steam boilers and 10 more particularly to boilers for use on steam automobiles and has for its object the provision of improved means for forming a combustible mixture which is supplied to the usual burners with which the boilers are ordinarily equipped.

The novel features of the invention will be apparent from the following description, taken in connection with the accompanying drawing, in which:

20 Figure 1 is an elevation of an apparatus embodying my invention, certain parts being shown in section; Fig. 2 is a section on the line 2—2 of Fig. 1; and Fig. 3 is a modification of a part of the apparatus.

25 Referring to the drawings, 10 indicates the usual boiler which is provided with the burner 11, this burner being of any suitable construction and shown in the form of a shallow pan provided with a perforated

30 cover. Surrounding the burner 11 and inclosing the lower side thereof is a wall 12 provided with circumferential openings 13. The wall 12 is spaced from the bottom of the burner 11 and forms a chamber to which air 35 is supplied by means of the openings 13 and from which it passes by means of the pipe 14 to the inlet 15 of a fan casing 16. Arranged in the fan casing 16 is a fan 17 which is mounted on the shaft 18 of a motor 19.

40 Hydrocarbon fuel is usually employed in connection with automobile boilers and I have shown a fuel supply pipe 20, the upper end of which is provided with the nozzle openings 21 which are adapted to spray the

45 fuel into the center of the fan 17 where it will unite with the current of air passing through the inlet 15. The fan, revolving at high speed, will break up the fuel into very

fine particles which will readily vaporize and form a perfect mixture which is discharged from the casing 16 through a pipe 50 22 to the burner 11. The fan 17 thus serves two functions, one being to draw the air through the inlets 13 to the chamber between the burner 11 and the wall 12 where it is 55 preliminarily heated, and the other being to break up the fuel into a finely divided state so that it will readily vaporize.

In Fig. 3 I have shown a modification, of a portion of the apparatus, in which the nozzle openings 21^a of the fuel pipe 20^a discharge the fuel into a chamber 23 from which it passes through the port 24 to the fan 17. The chamber 23 and the pipe 20^a constitute a carbureter, the chamber 23 being 65 a mixing chamber.

By means of my improved apparatus, I am enabled to form a more perfect mixture of the fuel and air than has been heretofore formed in the burners of automobile boilers 70 and by arranging to pass the air below the burner 11 before it passes to the mixing device, the efficiency of the apparatus is materially increased, the heating of the air facilitating the vaporization of the fuel. 75

Having thus described my invention, what I claim is:

In apparatus of the class described, the combination of a burner, a casing inclosing one side of the burner and provided with peripheral opening for the admission of air, an outlet from said casing, an inlet to said burner, a passage connecting said outlet with said inlet, a rotary fan in said passage, a liquid fuel supply nozzle in said passage, 85 and a motor for operating said fan, the parts being so arranged that the fuel is broken up and thoroughly mixed with the air by said fan.

In testimony whereof I affix my signature 90 in presence of two witnesses.

JOHN ASHTON DOBLE.
